UNITED STATES PATENT OFFICE

HERMANN MALY, OF GUBEN, GERMANY

TREATING FABRICS

Application filed November 7, 1928, Serial No. 317,802, and in Germany November 17, 1927.

My invention relates to a process for pre-heating, squeezing, steaming, and finish drying fabrics in one continuous operation, and to an apparatus intended for carrying out 5 this process.

In the process of drying fabric in the usual tentering and drying machines, the fabric retains the more or less smooth condition in which it reaches the machines. In 10 all cases the web, in the condition as it comes from the washing apparatus and after having been dried by centrifugalization or suction, is fed to the drying machine with all the creases that arose previously. The 15 consequence thereof is that the dried web subsequently must be subjected to a very intense dry-hot squeezing operation and intense dry steaming by very hot steam, to impart to it a creaseless smooth appearance.

20 By these drastic dry-hot operations, however, hitherto considered as necessary, the web, or the fibrous material it consists of, is seriously injured.

Now my present invention has for its object to so treat the wet web in one uninterrupted operation previous to the usual drying operation, by squeezing it in a hot cylinder press and simultaneously steaming it under this pressure, that the creases which 30 arose during the extraction of the water and the drying operation are thoroughly removed.

I realize this problem by using the moisture still existing in the already squeezed 35 web and amounting about to 40 percent, to revive the fibrous material the web consists of, and to protect the material from being burnt due to drying. The subsequent finish drying operation employed in a very mild 40 degree then definitely establishes the smooth condition of the web.

While in the hitherto usual operation the individual steps followed one another in the order drying, squeezing, steaming, these 45 operations with my new process are performed in following order: squeezing, steaming, drying, the entire treatment being performed in one continuous operation.

My new method may also be employed 50 previously to teasing the webs, in order to

feed to the teaseler a web in entirely smooth condition. This results in an absolutely uniform teasing effect, because an absolutely uniform smooth surface is offered to the teasels, which consequently have the possibility to likewise act uniformly. 55

The apparatus intended to carry out my new process partly comprises known and partly new elements. A new element consists in a press composed of a pressing cylinder and a trough or concave, and in a feed guide for the web, this guide serving to pre-heat the web before it arrives between the pressing cylinder and the trough. A further new element consists in guiding the 60 web further around said cylinder for the subsequent finish drying. The squeezing and finish drying operations may, however, be performed by means of special heating means, such as heated cylinders. 70

In order to allow of my invention to be more easily understood, a preferred embodiment of the apparatus serving to carry it out and two modifications thereof are illustrated by way of example in the accompanying 75 drawing.

While not yet squeezed, the web *a* to be treated is guided by rollers *b* through a suction device *c* of known design, the water extracted from the web being collected in 80 the tank *d*. Thereupon the web thus pre-dried is guided over a transverse stretcher *e* formed by suitable hackle or gripper chains, and over a guiding cylinder *f*, which in the embodiment illustrated in Figure 1, at the 85 same time forms a temple. The location of this cylinder is so determined that the pre-dried web comes into preliminary contact with a heated squeezing cylinder *h* at the point denoted by *g*, on which cylinder the 90 web is then pre-heated on the section *g-i*. Thereupon the web passes from *i* to *k* between the squeezing cylinder *h* and the trough *m*, which latter may be likewise heated. On the way from *i* to *k* the web 95 is subjected both to vaporization of its moisture and to a squeezing pressure. The steam generated hereby cannot escape, since the web constitutes its own packing means. Now, as it is well-known, any fibre is in the 100

most tractable condition as long as it is in a hot and wet condition, and this property in many cases is troublesome, e. g., in coloring, heating, and washing fabrics, as it provokes 5 undesirable felting; in the present process, however, this property has a favorable effect in realizing the object aimed at.

From the point *k*, where the web leaves the gap existing between the cylinder *h* and 10 trough *m*, up to the point *n*, where it gradually passes over to the guide roller *o*, the web is completely dried by said cylinder *h*, and leaves the apparatus. When the web should be beamed up after having been treated according to my new process in the described 15 cylinder-trough press *h*, *m*, it may immediately be supplied from guide roller *o* to a beam *r*, as illustrated in Figure 2. If required, the roller *o* may be heated inside, so 20 that a further finish drying takes place thereon.

In Figure 3 is shown a different manner 25 of guiding the web before entering and after leaving the cylinder-trough press *h*, *m*. In this modification two stationary or rotary heating bodies *x*, *y* are arranged beside the trough *m* instead of the temple cylinder *f* and guiding cylinder *o* of Figure 1, around which bodies the web *a* is guided. In this 30 case too the cylinder *x* may serve as temple.

In treating webs according to my described process, climatic conditions are of no influence on the fabric, more particularly as the material may be subjected to the described treatment in a more wet condition than caused by the moist climate of many tropical countries.

What I claim and desire to secure by Letters Patent, is:—

40 1. Apparatus for treating fabrics comprising a heated cylinder element and a concave element between which a moist fabric web is adapted to be passed to be squeezed and steamed, means for pre-heating the web 45 immediately prior to its confinement between said elements, a tenter and a temple preceding said preheating means in the order named, and means for drying the web immediately subsequent to its confinement between said elements.

2. Apparatus for treating fabrics comprising a heated cylinder element and a concave element between which a moist fabric web is adapted to be passed to be squeezed and steamed, means for pre-heating the web comprising a temple for guiding the web in contact with the cylinder element in advance of the concave element, and means for drying the web comprising a member for guiding the web in contact with the cylinder element to the rear of the concave element.

3. Structure in accordance with claim 2 wherein the last named guiding member is in the form of a heated roll.

65 4. Structure in accordance with claim 1

wherein a suction device precedes said tenter and temple.

5. Apparatus for heating fabrics comprising a heated cylinder element and a concave element between which a moist fabric web is adapted to be passed to be squeezed and steamed, a pre-heating roll for the web immediately in advance of said elements, and a heated drying roll immediately behind said elements.

6. Structure according to claim 5 wherein the pre-heating roll serves as temple.

In testimony whereof I affix my signature.

HERMANN MALY.
